UNITED STATES PATENT OFFICE.

ALFRED BARKER DUFF, OF PITTSBURGH, PENNSYLVANIA.

GAS-PRODUCER.

1,010,242.

Specification of Letters Patent. Patented Nov. 28, 1911.

Application filed March 21, 1910. Serial No. 550,716.

To all whom it may concern:

Be it known that I, ALFRED BARKER DUFF, a subject of the King of Great Britain and Ireland, and a resident of Pittsburgh, Pennsylvania, United States of America, have invented certain new and useful Improvements in Gas-Producers, and of which the following is the specification.

This invention relates to gas producers of the type having a water-cooled and water-luted revolving top and water-cooled adjustable pokers, and has for its object to provide an improved combination and arrangement of parts which will insure a thorough disturbance of the top layer of fuel, thus preventing clinkering and caking of the fuel, and insuring complete gasification thereof, the producer being particularly suitable for ammonia recovery purposes.

In carrying out the invention, the fire-brick lined casing and the blower are of usual construction and stationary. The top is water-cooled and water-luted and it is carried by a flange depending from its under side and bearing on rollers in the lute, so that rotation is permitted, while the bearings are kept free from dust or grit. The rotation of the top is effected through gearing from any suitable source of power, while a gas-tight joint between the top and casing is obtained by the flange in the water lute. Water-cooled pokers are pivoted at or near their centers in the top, their lower ends projecting into the upper parts of the fuel, and their upper ends engage each a nut working on a rotatable screwed spindle, so that the lower ends of the pokers may be moved to and from the sides of the casing, or adjusted in position relative to the sides, while also being carried around with the revolving top; thereby insuring the breaking up of any particular part of the upper layer of fuel.

In order that the invention and the manner of performing the same may be properly understood there are hereunto appended a sheet of explanatory drawings in which—

Figure 1 is a vertical section of parts of a producer sufficient to show the improved combination and arrangement, Fig. 2 being a plan of the top of the producer.

As shown in the drawings, the producer consists of the usual firebrick-lined casing A which is circular and carried on angle-iron beams B extending across the water-lute ash trough C from which the ashes are with-

drawn and from which extends up the usual blower grate D. In the center of the cover or top E of the producer is the usual feed hopper F, and the gas produced passes off by the outlet G. From the under side of the top E there projects an annular flange H, the lower edge of which runs on rollers J in the bottom of an annular channel K formed around the upper end of the producer casing A, and on the channel being filled with water the top is luted, making an effectual gas-tight joint between the casing and top, while the roller bearings being in the water-lute are kept free from dust or grit, while the lute itself being beyond the producer wall is not subjected to great heat. On the outer edge of the top E there is a toothed ring L gearing with a pinion M on a shaft driven through suitable gearing (not shown) from any suitable source of power, so that on rotation of the shaft the top E is made to revolve on the rollers J, displacement of the top being prevented by guide rollers N.

Pokers P have formed on them near the center of their length trunnions Q carried in bearings formed or fixed in the top E, so that the lower ends of the pokers project into the upper layer of the fuel within the producer, and the upper end of each poker engages in a slot in a nut R on a screwed spindle S carried in bearings on the upper ends of standards T extending up from brackets U secured to the hopper F. Each spindle S has on it a wormwheel V gearing with a worm W on the handled spindle X on turning which the screwed spindles S are rotated, causing the nuts R to travel thereon, and thus adjust the position of the pokers P. The pokers are preferably water-cooled, the water being supplied thereto through a swivel-jointed pipe Y connected by flexible pipes Z with the upper ends of the pipes dipping down within the pokers in known manner, the water overflowing from the pokers by pipes A¹ on to the upper surface of the top E from which it escapes by pipes B¹ into the annular channel K from which it overflows by a pipe C¹. Thus, while the burning of the pokers and top is prevented, a constant depth of lute in the channel K is also insured.

The combination of the novel arrangement for rocking the pokers with the circular movement imparted to them by the rotation of the top insures a thorough dis-

turbance of the top layer of fuel, which prevents clinkering and caking and aids gasification.

What I claim is:—

- 5 In a gas producer, a revoluble water-luted and water-cooled top, water-cooled pokers journaled in the top, means for adjusting the position of the pokers while they are revolving with the top said means comprising
- 10 ing nuts engaging the upper ends of the

pokers and rotatable screwed spindles on which the nuts work.

In testimony whereof I have signed my name to this specification, in the presence of two subscribing witnesses.

ALFRED BARKER DUFF.
